UNITED STATES PATENT OFFICE.

JOSE POWER Y ZABALA, OF DUNDEE, SCOTLAND.

MACHINE FOR SEWING PLAITED SOLES.

1,247,002.

Specification of Letters Patent.

Patented Nov. 20, 1917.

Application filed June 9, 1915. Serial No. 33,002.

To all whom it may concern:

Be it known that I, JOSE POWER Y ZABALA, of Bilbao, Spain, a subject of the King of Spain, residing at Viewpark, West Ferry, 5 Dundee, Scotland, have invented new and useful Improvements in a Machine for Sewing Plaited Soles, of which the following is a specification.

This invention relates to a machine for 10 sewing plaited soles.

Large quantities of plaited soles have been 15 sewn by hand, each sole being first sewn transversely right through the center and then three or more plaits are sewn together at the toe and at the heel, the sewing being more or less radial.

In this radial sewing the thread passes 20 through the sole at an angle, that is the needle is inserted at one corner of the edge and comes out at the opposite face of the sole.

In my invention the toe and heel sewing is 25 first effected and because such is the case the series of plaits at the toe and the heel can be firmly sewn together, the sewing needle and the thread passing through the center of the plaits, with the result that the thread is protected from wear for the longest possible period of time.

30 In order that my said invention and the manner of putting the same into practice may be properly understood, I have heretounto appended four explanatory sheets of drawings in which the same reference numerals are used to indicate corresponding parts in the figures shown:—

Figure 1 is a face view of the machine with the former removed.

40 Fig. 2 is a view looking in the direction of the arrow A (Fig. 1) the fly wheel being indicated by dotted lines.

Fig. 3 is a plan of the intermittent feed disk and shaft.

45 Fig. 4 is a side view of the appliance or former for holding the sole while it is being sewn and

Fig. 5 is a face view of same looking from the right of Fig. 4.

50 Fig. 6 is a part view of Fig. 1 showing the starting and stopping motion.

Fig. 7 is a view looking in the direction of the arrow B (Fig. 6.)

Fig. 8 is a plan.

55 Fig. 9 is an enlarged face view of the appliance for holding the sole while it is being sewn.

Fig. 10 is a side view of same.

Fig. 11 shows a detail, in end and in side elevation, the right hand view disclosing the detail as viewed in Fig. 2; and

60 Fig. 12 shows another detail, as viewed in Fig. 1.

The needle is made to reciprocate in the usual manner by means of a cam 3, and cam roller 4.

65 The shuttle 5 reciprocates in a path at right angles to the path of the needle, being operated by a carrier 6 whose motion is regulated in the usual fashion by a rotatory cam 7. 8 is a counterbalance weight on the 70 cam 7. 9 is the guide rod, 10 the cam roller and 11 a steadyng guide.

The shuttle and its carrier moves in a 75 guide 12 being located behind said guide and the front of the guide is behind the needle and consequently there is an aperture 13 in the front of the guide through which the loop of the needle thread can pass, in order that the shuttle can pass through it at the correct time.

80 Attached to the front of the machine is a bracket 14 which carries the device for supporting the former 15 and the sole 16 it carries when it is being sewn. This device consists of a non-rotatory slidable shaft 17 85 whose axis is at right angles to the face of the shuttle guide and central to the aperture 13 through which the needle thread loops.

The end of the shaft 17 next the shuttle guide is forked; that is it is recessed at 30 in 90 order that when it is pressed against this guide 12 the needle can freely pass down through it and form the loop when it is on its return journey.

95 The shaft 17 can be drawn back clear of the needle by means of a spring lever 18 being retained in that position by a side catch in the guide 19 as long as is desired. When thus drawn back the former 15 can be slipped over and supported by the forked 100 end of the shaft.

The former 15 consists of a semi-circular toothed wheel 20 to which is fixed a guide 21, it having an open center with ratchet teeth 22 on each internal face. At the 105 other end of the guide is a similar semi-circular wheel 23 and this wheel can be made to slide backward and forward on the guide. Carried by this wheel are two spring pawls 24 which can engage with the two ratchets 110 22 unless otherwise constrained. At the center of each wheel is a hole 25 into which

the forked end of the supporting shaft 17 can pass in turn.

Each semi-circular wheel is mounted on and is capable of rotating on a hub 26 carrying with it the former, the wheel being retained in a groove formed by a ruff 27 on the hub and situated on the one side of the wheel and a screwed nut 28 on the other side. This hub when mounted on its shaft 17 is retained in a fixed position by a fixed pin or key 29^a which is carried by the shaft 17. The outside face of the hub has a recess corresponding to the recess 30 in the end of the shaft and these are retained in their relative positions by the above mentioned key. The sole 16 which is to be sewn is stretched between the two hubs and made taut by pulling apart the slideable wheel 23, the two pawls 24 retaining it in that position until they are released.

After the former is hung on the supporting shaft 17, the spring lever 18 is released thus causing the end of the shaft to move forward and bear against the shuttle guide 12 at the same time pressing the sole between the face of the former and the face of the shuttle guide.

When the former is placed in position it lies at an angle, as shown in Fig. 5 which is determined by means of an adjustable guide.

The operation of the stitching means, comprising the fixed guide 12, the vertically reciprocating needle 1 in front of the guide, and the horizontally reciprocating shuttle 5 in rear of the guide, is as follows: It will be seen from Fig. 1 that the path of the needle is across the aperture 13 through the plate 12, the aperture thus being in position to have the loop of thread thrown there through toward the path of reciprocation of the shuttle, after the needle starts on its up-stroke after piercing the material to be sewn. This material is the sole 16 carried by the former 15. When the former 15 is mounted on the apparatus of Figs. 1 and 2, in the relation indicated, an end part of the sole 16 is positioned in the path of descent of the needle, above the aperture 13 in the guide 12. Therefore, the needle during each down-stroke and following up-stroke, pierces the sole 16, enters the recess 30 cut in the inner ends of the hub 26 and the shaft 17 and thereby comes opposite the aperture 13 in the guide 12, throws its thread loop through the aperture, and rises again to its elevated position after the loop is engaged by the horizontally moving shuttle 5 on the other side of the guide 12.

When the sole is being sewn the former 60 and with it the sole is moved around step by step by means of a small driving pinion 31 gearing into the teeth of the segment.

The pinion is on the extremity of a shaft 32 and the shaft is intermittently turned by 65 means of a star wheel 33 carried by it, the

star wheel being operated by a rotating face wheel 34 having in it a pocket 35 with angled bridge pin 36 which in its passage moves the star wheel one tooth. The length of the stitch can be varied, if desired by 70 varying the number of teeth in the driving pinion 31.

From the foregoing it will be understood that a series of plaits can be sewn together either at the toe or the heel, the radial and 75 central sewing commencing at one side of the sole and passing around to the other side.

In order that the machine may always stop at the same place an adjustable duplex 80 stop motion is provided.

The machine is driven by a belt pulley 37 the pulley operating the machine through a clutch.

On a shaft 38 operated from the driving 85 shaft by means of change gear 39 (so that its rate of rotation can be altered; thus determining the number of stitches to be sewn) is a disk 40 in whose periphery is a gap or recess 41.

Pressing against the periphery of the disk by means of a spring 42 is a roller 43 carried by a lever 44 and another extremity 45 of this lever is coupled to another lever 46 on an upright shaft 47, this shaft also carrying the clutch lever 48.

When the roller of the first mentioned lever 44 falls into the gap in the disk, its movement causes the clutch to disengage, and thus stop the machine.

In order to assist in the overcoming of the inertia of the moving parts; there is a secondary and positive stop motion. This motion consists of a pin 49 which projects from the shuttle cam and which is caught at the 105 proper moment by means of a pivoted lever 50 provided at the upper extremity with a hook 51 which may be cushioned at 52. The moment when the pin engages with the hook is when the needle is fully up. The hook 110 lever is disengaged from its pin by the spring foot lever 44 at the time this foot lever is used to disengage the lever from the gap 41 in the disk; this movement causing the clutch to engage and the machine to operate again. As long as the lever 44 is depressed the lever 50 is away from the path of the pin 49 but when the roller 43 falls into the gap 41 the lever 44 rises thus permitting the lever 50 to be drawn into the 120 path of the pin by means of the spring 53.

I claim;—

1. In a machine for sewing the heel and toe portions of plaited soles, the combination of a former upon which the plait to be 125 sewn is wound, a slideable shaft forming part of said machine for carrying said former, a hub at either end of said former for mounting said former on said slideable shaft and means for partially rotating either 130

end of said former about the axis of the
slidable shaft.

2. In a machine for sewing heel and toe
portions of plaited soles, the combination of
5 a former upon which the plait to be sewn is
wound, a slidable shaft forming part of said
machine for carrying said former, a hollow
hub at either end of said former for mount-
ing said former on said slidable shaft, a
10 semicircular tooth wheel at either end of
said former and a shaft carried by said ma-
chine and having a tooth wheel mounted
thereon for partially rotating said former.

3. In a machine for sewing heel and toe
15 portions of plaited soles, the combination of
a former upon which the plait to be sewn is
wound, a slidable shaft forming part of said
machine for carrying said former, a hollow
hub at either end of said former for mount-
20 ing said former on said slidable shaft, a
semicircular tooth wheel at either end of
said former, a shaft carried by said ma-
chine having a tooth wheel mounted thereon
for driving said former, and means for in-
25 creasing or decreasing the distance between
the hubs of the former.

4. In a machine for sewing heel and toe
portions of plaited soles, the combination of
a former upon which the plait to be sewn is
wound, a slidable shaft mounted in a bearing
29 on said machine for carrying said

former, a hollow hub at either end of said
former for mounting said former on said
slidable shaft, a semicircular tooth wheel at
either end of said former and a shaft carried
by said machine having a tooth wheel
35 mounted thereon for driving said former, a
guide forming part of said former, teeth cut
in said guide and pawls mounted on one end
of said former to engage said teeth for in-
creasing or decreasing the distance between
40 the hubs of the former.

5. In a machine for sewing heel and toe
portions of plaited soles, the combination of
a former upon which the plait to be sewn
is wound, a slidable shaft forming part of
said machine for carrying said former, a
shaft carried by said machine having a tooth
45 wheel mounted thereon for driving said
former, a star wheel carried by said shaft,
a rotating face wheel having in it a pocket
and an angled bridge pin and carried by a
rotatable shaft for intermittently rotating
50 the former.

In testimony whereof I have signed my
name to this specification in the presence of
two subscribing witnesses.

JOSE POWER y ZABALA.
